UNITED STATES PATENT OFFICE.

RICHARD K. HOHMANN, OF BELVIDERE, ILLINOIS, ASSIGNOR TO NATIONAL SEWING MACHINE COMPANY, OF BELVIDERE, ILLINOIS, A CORPORATION OF ILLINOIS.

REVOLVING-HOOK SEWING-MACHINE.

1,091,062.

Specification of Letters Patent. Patented Mar. 24, 1914.

Application filed May 5, 1913. Serial No. 765,417.

To all whom it may concern:

Be it known that I, RICHARD K. HOHMANN, a citizen of the United States, and resident of Belvidere, county of Boone, 5 and State of Illinois, have invented certain new and useful Improvements in Revolving-Hook Sewing-Machines, of which the following is a specification.

This invention relates to sewing machines 10 of the revolving hook type and has particular reference to the means for retaining the bobbin holder against rotation while permitting a loop of thread to pass freely around it.

15 The novel features of the invention will be apparent from the following description, taken in connection with the drawings.

In the drawings, Figure 1 is an end view 20 of a machine showing my invention applied thereto; Fig. 2 is a detail view of the spool holder with the operating means in a different position; Fig. 3 is a longitudinal section through a machine embodying the invention; Fig. 4 is a bottom plan view; 25 and Fig. 5 is a vertical section on the line 5—5 of Fig. 3.

The particular machine to which I have shown my invention applied is of the commercial type and some of the features of 30 this machine are covered by other applications which I am filing herewith.

The machine includes a base 1 carrying a rotary shaft 2 which operates the revolving hook ring 3. An upright hollow stand- 35 ard 4 carries the shaft 5 driven from the drive shaft 6 in the hollow horizontal arm 7. The drive shaft 6 operates the needle bar 8 carried in the head 9 of the machine and the shaft 6 is driven in any suitable 40 way through the pulley 10. The shaft 5 has a bevel gear 11 on its lower end meshing with a bevel gear on the end of the shaft 2 whereby the shaft 2 will make two revolutions for each revolution of the shaft 5, 45 and by this means it will be observed that the revolving hook makes two revolutions each time the needle reciprocates. The rotary hook is arranged below the elevated cloth plate 12, and that cloth plate has 50 a movable section 13 in advance of the line followed by the stitch and a shield 14 extends downwardly from that section around the working parts beneath the plate. A link 15 is pivoted to the two 55 parts of the work plate at an angle and a

guide plate 16 is secured to the under surface of the fixed part of the plate at the rear edge. A projecting plate 17 is secured to the under surface of the movable part on the opposite side and it enters a socket 18 60 on the fixed part. This construction permits the forward part of the work plate to be moved out of the way so as to give access to the rotary hook and other mechanism below the plate, and these features are made the 65 subject of a separate application.

The bobbin holder 19 has a bearing rim fitting within a bearing groove in the revolving hook ring 3, and it is provided with a hook 20 near the top and facing the top 70 for the purpose of engaging and spreading the loop of thread. A bobbin 21 is adapted to be placed within the holder with its axis parallel to the axis of the bearing rim but not concentric therewith being eccentric on 75 the side opposite to that on which the hook is placed. The bobbin passes through an opening on one side of the holder over a column or post which carries a member 22 longitudinally movable therein which has 80 fitted to its end the retaining arm 23. This retaining arm extends out to the edge of the bobbin and is curved down over the edge within the margin of the holder and it serves the double purpose of holding the 85 bobbin in place and offering some resistance to its turning movement, thus placing tension on the thread drawn from the bobbin. These features are also made the subject of a 90 separate application.

The present invention relates to the means for retaining the holder against rotation and that means includes an arm 24 rigidly secured to some part of the frame of the machine and having its end 25 extending downwardly into the path of a portion of the holder so as to prevent any material turning movement. In the particular form shown the arm 24 has its end curved and extends very slightly within a depression or opening 26 in the face of the holder immediately behind the hook 20 and in the upper part of the holder. The depression or opening 26 is wider than the end 25 of the arm 24 and therefore when the arm occupies a position in the center of the opening a loop of thread may easily and freely pass down between the end and the holder without meeting any resistance. On the side of the holder opposite the arm 24 I make use 100 105 110

of a finger 27 having an upwardly inclined under surface making contact with the upper end of the projection 28 on the holder which has an upwardly inclined under surface. The finger 27 is carried on the end of the arm 29 pivoted at 30 and adapted to rock so as to bring the finger 27 into and out of contact with the projection 28. When the finger 27 is in contact with the projection as shown in Fig. 2 the holder is moved or rotated slightly in the reverse direction to the movement which the rotary hook tends to give to it and it is moved only to such an extent as to bring the end 25 of arm 24 into the center part of the opening or depression out of contact with any part of the holder. When the finger 27 is in contact with the projection 28 it will prevent any turning under the influence of the rotary hook and thus the end 25 of arm 24 is held out of contact with the walls of the opening into which it projects. The operation of the arm 29 is so timed that the finger 27 will engage the holder as the loop is being carried down by the hook 31 toward the arm 24, and therefore the loop can pass freely beneath it. After the loop passes the end 25 the arm 29 moves back carrying the finger 27 out of contact with the projection 28 and thus the loop can ride up the inclined surface of the projection 28 and passes the end of the finger 27 freely. The end surface of the finger 27 being upwardly inclined avoids the possibility of catching the thread and this inclined arrangement is utilized to engage and depress the projection 28 turning the holder as above described. In order to guard against an accidental engagement of the loop with the arm 24 I preferably secure to it a guide 32 which extends upwardly toward the hook 20 so as to guide the loop down to the point of the arm 24.

It will be understood that in its broader aspects my invention is not limited to the particular means for causing the slight relative movement between the retaining arm 24 and the bobbin holder so as to permit the loop to pass freely between them and is furthermore not limited to the particular means for operating the finger 27. I have shown the finger 27 operated from the same shaft which operates the feed mechanism.

As shown in the drawings the feed member 33 is pivoted at one end to an arm 34 carried on the rock shaft 35 and the rock shaft 35 is given an oscillating movement by means of the link arm 36 which is given a longitudinal movement by the means shown in Fig. 5. That means constitutes the subject of another application but it includes a sliding block 37 guided by the parallel arms 38 on the end of the link arm 36 and an eccentric 39 works in that slide block and is secured to the shaft 6. A link arm 40 is pivotally connected to the link

arm 36 between its ends and extends therefrom at an angle being pivotally connected at its other end to the bell crank 41. The bell crank can be turned by a thumb screw 42 to different positions along the slot 43 so as to vary the angle of the link arm 40 to the link arm 36 and to thereby vary the amount of movement imparted to the shaft 35 and consequently the length of the longitudinal movement of the feed bar 33. The feed bar is given its up and down movement by the rock shaft 44 which is oscillated by the link 45 operated by the eccentric 46 on shaft 6. There is a link connection between an arm on shaft 44 and the end of the feed member 33 consisting of the rod 47 having ball and socket connections at its ends and the spring 48.

The rocking arm 29 is operated from the rock shaft 44 which gives the up and down movement to the feed bar by means of an arm 49 and a link 50 and since the shaft 44 makes only one oscillating movement during two revolutions of the revolving hook it will be observed that the finger 27 will be brought into engagement with the holder but once during two revolutions of the hook and as above stated this action is so timed that it will occur just as the hook is carrying the loop of thread down toward the arm 24.

Having thus described my invention, what I claim is:

1. In a revolving hook sewing machine, the combination with a bobbin holder, of a rotary hook for passing a loop of thread around said holder, a fixed arm projecting slightly into an opening in the face of said holder on one side to prevent its rotation, and a rocking arm on the opposite side of said holder below the top for engaging said holder on its inward movement to turn it sufficiently to bring it into a position where the fixed arm will be out of contact with the walls of said opening in said holder and means for operating said rocking arm at each alternate revolution of the rotary hook.

2. In a sewing machine, the combination with a bobbin holder having a hook for spreading a loop of thread and an opening in the upper part of its face behind said hook, of a revolving hook for passing said loop around said holder, a fixed arm having a downwardly inclined end projecting slightly into said opening to prevent the rotation of said holder, and means for moving said holder to such an extent that said arm will be out of contact with the walls of said opening in said holder when said loop approaches said arm thus allowing a free passage of the loop beneath said arm.

3. In a sewing machine, the combination with a bobbin holder having a hook for spreading a loop of thread and an opening in the upper part of its face behind said

hook, of a revolving hook for passing said loop around said holder, a fixed arm having a downwardly inclined end projecting slightly into said opening to prevent the rotation of said holder, and a movable finger having an upwardly inclined under surface adapted to engage the upper portion of said holder on the side opposite to said fixed arm and below the top to move it slightly, and means for operating said movable finger.

4. In a sewing machine, the combination with a bobbin holder having a hook for spreading a loop of thread and an opening in the upper part of its face behind said hook, of a revolving hook for passing said loop around said holder, a fixed arm having a downwardly inclined end projecting slightly into said opening to prevent the rotation of said holder, a projection on the upper portion of the holder on the side opposite to said opening having an upwardly inclined lower surface, a movable finger having an upwardly inclined lower surface adapted to engage the upper end of said projection to move said holder slightly, and means for operating said movable finger.

5. In a sewing machine, the combination with a bobbin holder having a hook for spreading a loop of thread and an opening in the upper part of its face behind said hook, of a revolving hook for passing said loop around said holder, a fixed arm having a downwardly inclined end projecting slightly into said opening to prevent the rotation of said holder, a projection on the upper portion of the holder on the side opposite to said opening having an upwardly inclined lower surface, a rocking arm pivoted at its lower end and carrying a laterally projecting finger at its upper end having an upwardly inclined lower surface adapted to engage the top of said projection, and means for rocking said arm.

45 6. In a sewing machine, the combination with a bobbin holder having a hook for spreading a loop of thread and an opening in the upper part of its face behind said hook, of a revolving hook for passing said loop around said holder, a fixed arm having a downwardly inclined end projecting slightly into said opening to prevent the rotation of said holder, means for moving said holder to such an extent that said arm

55 will be out of contact with the walls of said

opening in said holder when said loop approaches said arm thus allowing a free passage of the loop beneath said arm, and a guide extending upwardly from said fixed arm for directing the loop of thread to the 60 point of said arm.

7. In a sewing machine, the combination with a needle and needle operating mechanism, of a cloth plate, a bobbin holder and a revolving hook carrying said holder below 65 said plate and adapted to pass a loop of thread around it, a cloth feeding member, means for reciprocating said member, means for raising and lowering said member at each alternate revolution of said revolving 70 hook including a rock shaft, means for preventing any substantial rotation of said holder while permitting the free passage of the loop around it including a fixed arm.

8. In a sewing machine, the combination 75 with a needle and needle operating mechanism, of a cloth plate, a bobbin holder and a revolving hook carrying said holder below said plate and adapted to pass a loop of thread around it, a cloth feeding member, 80 means for reciprocating said member, means for raising and lowering said member at each alternate revolution of said revolving hook including a rock shaft, means for preventing any substantial rotation of said holder 85 while permitting the free passage of the loop around it including an upwardly extended arm pivoted at its lower end carrying a finger at its upper end for engaging said holder, and link connections between 90 said arm and rock shaft for operating said finger to engage and disengage said holder.

9. In a revolving hook sewing machine, the combination with a bobbin holder, of a rotary hook for passing a loop of thread 95 around said holder, cloth feeding mechanism, an arm having its end in the path of said holder to prevent rotation, a movable arm adapted to engage said holder on the opposite side to rotate it slightly out of 10 contact with said first mentioned arm and means for operating said movable arm from said feed operating mechanism at each alternate revolution of the hook.

In testimony whereof I affix my signature 1
in presence of two witnesses.

RICHARD K. HOHMANN.
